(57) **CLAIM**

The ornamental design for electrical connector, as shown and described.

DESCRIPTION

FIG. 1 is a top, front, right-side perspective view of an electrical connector according to our new design;

FIG. 2 is a top, rear, right-side perspective view thereof;

FIG. 3 is a cutaway top, front, right-side perspective view

thereof;

FIG. 4 is a right-side elevation view thereof;

FIG. 5 is a left-side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The dot-dash broken lines represent boundaries of the claimed design and form no part of the claimed design. The dash-dash broken lines depict portions of the electrical connector that form no part of the claimed design.
